CLAIM

We claim the ornamental design for a hard-sided four-wheeled case, as shown and described.

DESCRIPTION

FIG. 1 is a front view of the hard-sided four-wheeled case with the handle partially raised;

FIG. 2 is a front perspective view thereof;

FIG. 3 is a left side view thereof;

FIG. 4 is a rear perspective view thereof;

FIG. 5 is a rear view of the hard-sided four-wheeled case with the handle lowered;

FIG. 6 is a right side view of the hard-sided four-wheeled case with the handle partially raised;

FIG. 7 is a front perspective view showing the front pocket in the open position;

FIG. 8 is a fragmentary top perspective view with the front pocket in the open position;

FIG. 9 is a fragmentary view of the control panel of the hard-sided four-wheeled case;

FIG. 10 is a bottom view of the hard-sided four-wheeled case; and,

FIG. 11 is a fragmentary view of the wheel of the hard-sided four-wheeled case.

The short broken line disclosure of the paper in FIG. 8 illustrates the environment and forms no part of the claimed design. The long dashed lines in FIGS. 7 and 8 illustrate stitching and form part of the claimed design.
